United States Patent Office

Des. 224,753

Patented Sept. 12, 1972

224,753

LUMINAIRE

Charles P. Breed, Alexandria, Va., Edmund L. Izzi, Pittsburgh, Pa., and Donald E. Husby, Fairview Park, Ohio, assignors to Westinghouse Electric Corporation

Filed Mar. 17, 1971, Ser. No. 125,457

Term of patent 14 years

Int. Cl. D26—03

U.S. Cl. D48—31

FIG. 7

FIG. 8

FIG. 9

FIG. 1 is a top plan view of a luminaire embodying our new design;

FIG. 2 is a front elevational view thereof;

FIG. 3 is a bottom plan view thereof;

FIG. 4 is a side elevational view thereof;

FIG. 5 is a perspective view thereof on a reduced scale;

FIG. 6 is a rear elevational view thereof;

FIG. 7 is a top plan view of a second embodiment of our design being a composite of six of the luminaires shown in FIGS. 1-6;

FIG. 8 is a front elevational view thereof; and

FIG. 9 is a bottom plan view thereof.

The support post is shown in broken lines in FIGS. 1-9 for illustrative purposes only.

What is claimed is:

The ornamental design for a luminaire, as shown and described.
